CANNED LIQUID SERVER

Franklin W. Sprout, Grass Valley, Calif.

Application May 13, 1940, Serial No. 335,015

5 Claims. (Cl. 65—61)

The invention relates to a canned liquid server and more especially to a device for holding and dispensing canned fluids, for example, evaporated milk, evaporated cream, syrups or the like.

The primary object of the invention is the provision of a device of this character wherein the cylindrical body thereof is formed in two sections, these being hinged together so as to permit the introduction and removal of canned fluid so that the contents of the can can be conveniently handled for the dispensing of the same, the device being adapted to open the can when the body of such device has been closed about the said can for the pouring of the contents and when the pouring has been completed the can will be sealed so as to avoid contamination of the remaining fluid therein or the possibility of such remaining contents becoming fermented and spoiling.

Another object of the invention is the provision of a device of this character wherein the body is formed with a pouring spout and also is effective for the opening of a can when confined therein so that the contents can be readily and conveniently poured and also such body of the device renders the canned fluid held therein thoroughly sanitary.

A further object of the invention is the provision of a device of this character wherein the contents of a can can be dispensed in its entirety or in determined quantities and the dispensing being conveniently executed and that portion of the contents that may remain in the can will be protected so that it will not become contaminated or quickly ferment and spoil, the device being especially designed for the purpose of using liquid directly from a can and at the same time keeping the can airtight.

A still further object of the invention is the provision of a device of this character, which is simple in its construction, thoroughly reliable and efficient in operation, readily and easily handled, neat in appearance, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a side elevation of the device con-

structed in accordance with the invention and in a resting position.

Figure 2 is a vertical longitudinal sectional view thereof.

Figure 3 is a side elevation showing the body of the device in open position.

Figure 4 is a top plan view of the device when the body is closed.

Similar reference characters indicate corresponding parts throughout the several views in the drawing.

Referring to the drawing in detail, A designates generally the device constituting the present invention and comprises a hollow body formed in two sections 10 and 11, respectively. These sections 10 and 11 are of rounded formation having outwardly bulged areas 12 merging into flange portions 13 which match each other when the said sections are brought together and constitute a rest rim at the bottom of said body. These sections 10 and 11 at the upper end of the body are joined by pivot hinges 14 which are arranged diametrically opposite each other at the line of separation for the said sections.

25 The section 10 of the body of the device A at the uppermost portion thereof is formed with a pouring spout 15 while the section 11 is built with a loop handle 16. The section 11 is provided at the uppermost end with a bearing 17 pivotally supporting at 18 a lever 19. The lever 19 at the end next to the handle 16 is formed with a finger grip 20 while at the proper point along said lever 19 are stoppers 21 and 22, respectively, for closing 30 passages through tubular piercing members 23 and 24, respectively, depending from the top portions of the sections 10 and 11. These members 23 and 24 are adapted to puncture the closed end of a can 25 when the latter is introduced into the body and the sections 10 and 11 closed about such can as does appear in Figures 1 and 2 of the drawing.

35 The puncture created by the member 23 is for dispensing therethrough the contents of such can while the puncture created by the member 24 effects an air vent to allow the contents of the can to freely pour therefrom, the dispensing of the contents being had through the spout 15. The lever 19 is acted upon by a spring 26 which urges the same to a position for the fitting of the 40 stoppers 21 and 22 in the passages through the members 23 and 24 for the closing of such passages when the device is at rest. The lever 19 is manually operated so that the passages through the members 23 and 24 can be opened when the can 25 is confined within the body of said device

to permit of the dispensing of the contents of said can when the device is tilted for this purpose.

Surrounding the members 23 and 24 are resilient sealing washers 27 which have contact with the top of the can 25 concentrically about the punctures therein created by the said members 23 and 24 and in this way eliminating leakage about said members.

The sections 10 and 11 of the body of the device are formed with bottom portions 28, these matching each other, and when the sections are brought together effect a bottom to the body of the device. One of the portions 28 carries a spring latch 29 for engaging a keeper 30 on the other portion 28 and in this way the sections 10 and 11 of the body are latched together for retaining and confining the can 25 within said body.

The sections 10 and 11 match each other and when the same are brought together will completely confine the can 25, which at its bottom end is brought to rest at 31 interiorly of the sections 10 and 11 when in closed, brought-together position. It should be noted by reference to the drawing that the can 25 on the bringing together of the sections 10 and 11 will be urged in the direction of the members 23 and 24 so that these through pressure of the can thereon will puncture the end of the can next thereto for the purposes hereinbefore stated.

On the placing of the can 25 within the sections 10 and 11 of the body of the device A, these sections will be brought together and latched so as to snugly confine the can 25 within the body of such device. When the can 25 is confined, as stated, it will have become punctured by the members 23 and 24 so that the contents of such can can be readily and easily dispensed in the use of the device. The dispensing of the contents of the can 25 can be had when the stoppers 21 and 22 are removed from the passages in the members 23 and 24 and the device brought to a tilting position for the dispensing operation.

When the stoppers 21 and 22 fit in the passages in the members 23 and 24, the can 25 within the device will be in a sealed condition and thus the contents of the can will be protected so as not to become contaminated as well as avoiding the fermenting and the spoiling of such contents.

When it is desired to remove the can 25 from the device, the sections 10 and 11 are unlatched and swung away from each other in the manner as appears in Figure 3 of the drawing. In this relationship of the sections 10 and 11 of the body of the device A, a can can be introduced or removed in an easy and convenient manner.

The portions 28 of the sections 10 and 11 have outwardly struck therefrom catch channels or grooves 32, which are in circular, spaced relation to each other so that should any waste of the liquid flow into the body of the device the same will be caught or trapped in the channel or groove. These outstruck channels or grooves 32 also reinforce the portions 28 for the strengthening of the same in the bottom end of the said device.

What is claimed is:

1. A device for fluid containers and the like, comprising a longitudinally divided casing forming matched separable sections, hinges at the uppermost end of the casing for swingingly connecting the sections together, puncturing mem-

bers on the sections at the hinged end of the casing and forming passages therethrough, means for closing and opening the passages through said members, means latching the sections together, and a pouring spout formed on one section at the hinged end of the casing next to a member having the passage therethrough.

2. A device for fluid containers and the like, comprising a longitudinally divided casing forming matched separable sections, hinges at the uppermost end of the casing for swingingly connecting the sections together, puncturing members on the sections at the hinged end of the casing and forming passages therethrough, means for closing and opening the passages through said members, means latching the sections together, a pouring spout formed on one section at the hinged end of the casing next to a member having the passage therethrough, and a handle on the other section.

3. A device for fluid containers and the like, comprising a longitudinally divided casing forming matched separable sections, hinges at the uppermost end of the casing for swingingly connecting the sections together, puncturing members on the sections at the hinged end of the casing and forming passages therethrough, means for closing and opening the passages through said members, means latching the sections together, a pouring spout formed on one section at the hinged end of the casing next to a member having the passage therethrough, a handle on the other section, and a spring-tensioned lever included in the means for closing and opening the passages in the said members.

4. A device for fluid containers and the like, comprising a longitudinally divided casing forming matched separable sections, hinges at the uppermost end of the casing for swingingly connecting the sections together, puncturing members on the sections at the hinged end of the casing and forming passages therethrough, means for closing and opening the passages through said members, means latching the sections together, a pouring spout formed on one section at the hinged end of the casing next to a member having the passage therethrough, a handle on the other section, a spring-tensioned lever included in the means for closing and opening the passages in the said members, and bottom portions formed on said sections at the lowermost end of the casing.

5. A device for fluid containers and the like, comprising a longitudinally divided casing forming matched separable sections, hinges at the uppermost end of the casing for swingingly connecting the sections together, puncturing members on the sections at the hinged end of the casing and forming passages therethrough, means for closing and opening the passages through said members, means latching the sections together, a pouring spout formed on one section at the hinged end of the casing next to a member having the passage therethrough, a handle on the other section, a spring-tensioned lever included in the means for closing and opening the passages in the said members, bottom portions formed on said sections at the lowermost end of the casing, and a rest rim built with said sections.

FRANKLIN W. SPROUT.
